PISTON EXPANDER

Harold P. Phillips, Hastings, Mich., assignor to
 Hastings Manufacturing Company, Hastings,
 Mich.

Application October 29, 1938, Serial No. 237,686

7 Claims. (Cl. 309—12)

The main objects of my invention are:

First, to provide a novel expander for pistons of the type having a skirt slot therein running only partly of the length of the skirt or no slot.

5 Second, to provide an expander for expanding the dimension of the piston at 90° to the wrist pin bearing to force the piston into an oval shape or a shape having an increased amount of oval.

Third, to provide a piston expander of the type 10 described which is very simple to install without extensive alteration of the piston.

Fourth, to provide an expander of the type described which is exceedingly inexpensive, being formed of inexpensive material and by a few 15 simple manufacturing operations.

Further objects relating to details and economies of my invention will definitely appear from the description to follow. The invention is defined in the claims.

20 A structure embodying the features of my invention is illustrated in the accompanying drawing, wherein:

Fig. 1 is a view in vertical longitudinal section through an internal combustion engine piston, illustrating one embodiment of the expander of 25 my invention in operative relation thereto.

Fig. 2 is a view illustrating the piston expander of my invention in the form which it takes when inserted in a piston the relaxed or unsprung position of the expander being indicated by dotted lines.

Fig. 3 is a view in section similar to Fig. 1, illustrating a slightly modified embodiment of the expander of my invention in a somewhat different type of piston from that of Fig. 1.

35 Fig. 4 is a view similar to Figs. 1 and 3, illustrating a still further embodiment of my invention.

Fig. 5 is a view similar to Figs. 1, 3, and 4, illustrating a still further form of expander contemplated by my invention.

40 Fig. 6 is a fragmentary view in section on line 6—6 of Fig. 5, further illustrating details of construction of that embodiment.

On certain types of piston, it is customary to 45 provide a generally axially disposed skirt slot which extends only partially of the length of the piston skirt, or else the slot is short and has both ends closed. Still other types of pistons have no skirt slots. In order to eliminate piston

50 rock and slap in worn cylinders, it is usual to expand the skirt of the piston by inserting an expander in the slot; however, in pistons of the variety which have either no skirt slot or an incomplete one, this is impossible or extremely 55 difficult without forcing the pistons into an objectionably oval shape. The herein described piston expander is especially designed for such an adaptation, although it will be apparent that it is also adapted for use in any piston, even one provided

60 with a full length slot. Generally speaking, the

expander of my invention is in the form of a U-shaped spring element having the free ends thereof secured to the piston skirt at points 90° from the wrist pin bearings, whereby an effective outward thrust normal to the said bearings is obtained, so that the dimension across the piston at 90° to the wrist pin bearings is increased to take up piston rock and slap.

Referring to the drawing, the reference numeral 1 in each of the figures designates an internal combustion engine piston which, as has been pointed out, may be of the type having an incomplete skirt slot i. e., one not extending to the edge of the skirt, or no slot at all or the usual full length slot, my invention being particularly devised for use in the case of a piston having an incomplete slot or none at all. The piston illustrated is of the thin walled skirt no-slot type. The expander, which is indicated by the reference numeral 2, is generally U-shaped in form and is 20 made of round spring wire of a diameter sufficient to produce the desired spring expansive force. The expander consists of a curved bight portion 3 and a pair of longitudinal leg portions 4, each, in the embodiment of Fig. 1, terminating in outward turned lugs 5 receivable in holes 6 drilled in the piston skirt for that purpose at 90° from the wrist pin bearings 61.

In the form illustrated in Figs. 1 and 2, it will be observed that the outline of the expander is 30 made up, in fact, of a plurality of smoothly converging curves, the bight 3 being of one radius of curvature while the leg portions 4 are of a greater radius of curvature. As a matter of fact, in the actual expander, no one of the bight or 35 leg portions is of a uniform circular curvature and it is necessary to form the expander by providing a plurality of continuously changing outline. I therefore do not wish to be restricted to an element having any particular type of curvilinear configuration except as limited by the 40 appended claims.

The leg portions 4 are offset inwardly at 7 prior to being bent outwardly at the lugs 5, so that the portion of the skirt on which the expansive action 45 of the expander 2 is exerted is clearly defined and localized along a definite length of the legs thereof.

In Fig. 3, I illustrate an expander which is generally similar in form and disposition with 50 respect to the piston to that illustrated in Fig. 1, being, however, characterized by a somewhat more exaggerated inward offsetting of the legs at 8 to space the points of thrust engagement 9 from the points of securement from the outwardly 55 disposed lugs 10 and a somewhat more uniform curvature.

In Fig. 4, the expander has leg portions 11 which are generally rectilinear and integrally connected to the curvilinear bight portion 12. 60

The lugs 13 for securing the expander to the piston are formed in a die by embossing the material of the expander to provide the aforesaid radially outwardly projecting lugs.

5 In Figs. 5 and 6, the expander is generally similar in form to that of Figs. 1, 2, and 3, having curved leg portions 14, and it is similar to all of the foregoing embodiments in that it is of a U-shaped outline, however the extremities of the 10 leg portions 14 are conformed into small circles or coils 15 bearing against the sides of the piston and terminate in the outwardly disposed lugs 16. The foresaid circular bearing portions lend somewhat to the stability of the expander in 15 installed position and are of advantage in distributing the thrust over larger areas in pistons having extremely thin walled skirts.

In actual practice, I have found it desirable to 20 use an expander spring wire which is plated to resist acid attacks from certain conditions which sometimes occur in internal combustion engines. Experience has shown that many piston expanders have been broken by hydrogen embrittlement brought about by acid present in the 25 lubricant, and I thereby contemplate an appropriate treatment of my expander to resist this condition.

I have illustrated and described my improvements in embodiments which are very practical. 30 I have not attempted to illustrate or describe other embodiments or adaptations as it is believed this enclosure will enable those skilled in the art to embody or adapt my improvements as may be desired.

35 Having thus described my invention, what I claim as new and desire to secure by Letters Patent is:

1. An expander for the skirt of an internal combustion engine piston, comprising a U-shaped 40 expanding member of circular section having a continuously curved bight portion and curved leg portions merging with said bight portion, said leg portions being offset radially inwardly then outwardly to provide lugs for mounting the expander on a piston skirt provided with diametrically opposed holes to receive the lugs, said radial inward offsetting of the leg portion defining a section thereof spaced substantially from said lugs for thrust engagement with the skirt at 45 points spaced substantially above the lowermost edge of the skirt and said lug receiving holes.

2. An expander for the skirt of an internal combustion engine piston, comprising a U-shaped expanding member of circular section having a continuously curved bight portion and curved leg 55 portions merging with said bight portion, said leg portions being offset radially outwardly to provide lugs for mounting the expander on a piston skirt provided with diametrically opposed holes to receive the lugs, said leg portions being curved for thrust engagement with the skirt at 60 points spaced substantially above the lowermost edge of the skirt and above said lug receiving holes.

65 3. In combination, a piston having a skirt provided with a continuous uninterrupted lower annular edge, and an expander for the skirt comprising a U-shaped expanding member having a continuously curved bight portion and leg portions smoothly merging with said bight portion, 70 said leg portions being offset radially inwardly

then outwardly to provide elements for mounting the expander in the piston skirt which is provided with means for receiving the elements, said radial inward offsetting of the leg portion defining a section thereof spaced substantially from said lugs for thrust engagement with the skirt at points spaced substantially above said lowermost edge and above the points of engagement of said elements with the skirt.

4. In combination, a piston having a skirt provided with a continuous uninterrupted lower annular edge, and an expander for the skirt comprising a U-shaped expanding member having a continuously curved bight portion and leg portions smoothly merging with said bight portion, said leg portions being offset radially outwardly to provide elements for mounting the expander in the piston skirt which is provided with means for receiving the elements, said leg portions being curved for engagement with said skirt at points substantially above the said edge and above the points of engagement of the elements with the skirt.

5. In combination, an internal combustion engine piston comprising a skirt having a continuous uninterrupted lower edge and a pair of wrist pin bearings, and an expander for the skirt comprising a generally U-shaped expander member of round spring stock, said member having legs provided with bearing portions and terminating in outwardly disposed lugs adapted to engage in the skirt, said bearing portions being spaced substantially from said lugs to engage and exert radial thrust on said skirt at points spaced substantially above said engine and the points of engagement of the lugs with the skirt, said expander being compressed and inserted in said skirt and in operative position being disposed at 90° to a line through the wrist pin bearings of the piston.

6. In combination, an internal combustion engine piston having a skirt which is continuous and uninterrupted at its lower edge and is provided with a pair of opposed holes, said holes being alined at 90° to a vertical plane through the 45 wrist pin bearings of the piston, and an expander for said skirt comprising a generally U-shaped spring member, said member having the legs thereof offset inwardly to define a skirt engaging section spaced substantially from the ends of the 50 legs and then radially outwardly to provide lugs engageable in said holes, said skirt engaging section engaging and exerting radial thrust on the skirt at points spaced substantially from the lower edge thereof and from said holes whereby to 55 exert deforming action on the piston approximately midway of the height thereof.

7. An expander for the skirt of an internal combustion engine piston, comprising a U-shaped expanding member having a curved bight portion 60 and legs merging with said bight portion, said legs being offset radially outwardly to provide lugs for engaging and mounting the expander on the piston skirt, said legs being formed between said lugs and bight portion for thrust engagement with the skirt at points spaced substantially above the lowermost edge of the skirt, and above the points on said skirt at which said lugs engage the same.
